UNITED STATES PATENT OFFICE.

HENRY C. HEINLE, JR., OF HUNTINGTON PARK, CALIFORNIA.

WARM-AIR LIBERATOR.

Application filed June 25, 1925. Serial No. 39,563.

This invention relates to enclosures, such as display cases, refrigerators and the like, and has more particular reference to a device for automatically liberating warm air 5 from such enclosures when their doors are closed and after such warm air has been admitted upon opening of the door.

It is well known that the temperature within a refrigerator or the like is frequently raised by the admission of warm air when the door of the same is opened, which warm air is trapped in the refrigerator when the door of the latter is closed, thus reducing the efficiency of the refrigerator and resulting in excessive and expensive use of ice for maintaining the interior of the refrigerator cool.

The present invention embodies a device for overcoming the above objections by preventing the escape of cool air from a refrigerator or the like under normal conditions, and for automatically liberating the warm air from the refrigerator upon closing the door of the latter.

An object of the invention is to provide a device of the above kind which is simple and durable in construction and efficient in operation.

Other objects will appear as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

Figure 1 is a substantially central vertical longitudinal sectional view of a warm air liberator constructed in accordance with the present invention,

Figure 2 is a view of the device shown in Figure 1 partly in plan, partly in horizontal section, and partly broken away,

Figure 3 is a substantially central, vertical, transverse sectional view thereof, and

Figure 4 is a diagrammatic vertical section of a refrigerator equipped with a pair of the devices shown in Figure 1.

Referring more in detail to the drawings, the warm air liberator embodies a casing composed of a tubular body 5 closed at its upper or outer end by means of a foraminous wall 6 of wire screen material or the like. A

tubular member 7 is fitted into the lower end of the body 5 and the walls of the same con-

verge upwardly so as to terminate in spaced relation to the walls of the body 5 at a point intermediate the ends of the latter. A valve plate 8 is hinged along one edge as 60 at 9 to the upper edge of one wall of the tubular member 7 and normally occupies a horizontal position for closing the upper end of the latter, the premarginal portions of the valve plate 8 resting on the upper edges 65 of the remaining walls of the member 7. The body 5 is provided at its ends with continuous outwardly projecting flanges 10 and 11.

As shown in Figure 4, the refrigerator or 70 the like is indicated at 12 and is provided with a hinged door 13 which swings inwardly to closed position, and associated with the top wall of the refrigerator are a plurality of these warm air liberating devices. 75 The body 5 of each device is fitted in an opening formed in the top wall of the refrigerator and the flanges 10 and 11 engage the outer and inner surfaces of said wall about the opening whereby the body 5 80 is secured in place. The inner flange may be secured in place after the body is placed in the opening, and any suitable means may be provided for securing such flange in place. As shown, the flanges are separate from the 85 body 5 and engage the ends thereof, the flange 10 being secured to the body by soldering, welding or the like and the flange 11 being held in place by the flange 14 formed on the lower end of the member 7. How- 90 ever, other fastening means, such as bolts or the like may be used if found necessary or desirable.

When the door 13 of the refrigerator 12 is opened, warm air is admitted to the interior of the refrigerator and rises to the top of the latter. Closing of the door 13 will cause compression of the air in the refrigerator so that the valve plate 8 is momentarily forced open or swung upwardly, and the 100 warm air is simultaneously forced out of the refrigerator through the body 5. As soon as the warm air is released, the compression of the air in the refrigerator is relieved and the valve plate 8 lowers by gravity to closed position so as to prevent the escape of cold air or the admission of warm air. The foraminous wall 6 permits the escape of the warm air and prevents objects from entering the body 5 and interfering with the operation of the valve plate 8.

One end of the body 5 is provided with an

inwardly projecting flange 15, the inner portion of which is depressed to set up the supporting ledge 16, the surface of which ledge is below the edges of the body walls so that 5 the screen 6, when placed thereon, will be flush with the end of the body. The flange 10 overlies the edges of the screen holding the same in position as shown.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:

1. In a device of the character described, a tubular body adapted to be fitted in the opening in the wall of an inclosure, an inwardly extending flange at one end of said body having the outer surface, adjacent the inner edge thereof, in a lower plane than the adjacent edge of said body to set up a supporting ledge, a foraminous body resting upon said supporting ledge and closing the adjacent edge of the body, continuous outwardly projecting flanges on the ends of the body adapted to engage the inner and outer surfaces of the wall about the opening for securing the body in position, one of said flanges overlying the inwardly extending flange of the body and acting to maintain said foraminous body in position, and a normally closed check valve plate arranged within the body intermediate the ends thereof and adapted to swing toward said foraminous body to open to permit the passage of air through the tubular body.
2. A warm air liberator including a tubular body adapted to be fitted in an opening in the wall of an inclosure, continuous out-

wardly projecting flanges on the ends of the body adapted to engage the inner and outer surfaces of the wall about the opening for 45 securing the body in the opening, a normally closed outwardly opening check-valve plate within the body intermediate the ends of the latter for controlling the passage of air therethrough, a tubular member fitted 50 into the lower end of the body, said check-valve plate being hinged along one edge to the upper edge of one wall of said tubular member and normally seating on the upper edges of the remaining walls of said tubular member for closing the upper end of the latter, the flange on the inner end of the body being separate from the latter, and a continuous outwardly projecting flange on the inner end of said tubular member engaging the inner margin of said inner flange of the body for retaining such flange in place against the inner surface of said wall.

3. A warm air separating device of the character set forth, comprising a tubular body adapted to be fitted in an opening in the wall of an enclosure, means for maintaining said body in position in said opening, a tubular member fitted into one end of said first mentioned tubular body, having the walls thereof converging toward the inner end to terminate in spaced relation to the walls of the surrounding body, said tubular member having the walls thereof provided with outwardly projecting flanges designed to engage over the adjacent end of the encasing body to maintain the tubular member in position therein, and a check valve plate mounted upon the inner edges of the walls of said tubular member, and having hinged connections with the adjacent edge of one of said walls.

In testimony whereof I affix my signature.
HENRY C. HEINLE, JR.
